Primary Examiner — Catherine S Posthauer*Assistant Examiner* — Yen Le Southwood(74) *Attorney, Agent, or Firm* — John J Aneway; Janeway Patent Law PLLC(57) **CLAIM**

The ornamental design for a cup, as shown and described.

DESCRIPTION

FIG. 1 is a perspective view of a cup, showing our new design;
 FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7. is a bottom plan view thereof; and,

FIG. 8 is a cross-sectional view thereof, taken as shown in FIG. 3.

The broken lines in FIGS. 1, 3, 7 and 8 are for the sole purpose of showing portions of the cup and do not form part of the claimed design.

1 Claim, 4 Drawing Sheets# US D1,096,318 S
